DESIGN FOR A TEXTILE FABRIC

Ralph J. Krause, New York, N. Y.

Application March 8, 1937, Serial No. 68,070

Term of patent 7 years

To all whom it may concern:

Be it known that I, Ralph J. Krause, a citizen of the United States and a resident of Manhattan, county of New York, and State of New York, have invented a new, original, and ornamental Design for a Textile Fabric, of which the following is a specification, reference being had to the accompanying drawing, forming part thereof.

The figure is a plan view of the fabric, showing my new design.

I claim:

The ornamental design for a textile fabric, as shown.

RALPH J. KRAUSE.
